CLAIM

The ornamental design for an electric breast pump, as shown and described.

DESCRIPTION

FIG. 1 is a perspective view of an electric breast pump of the present invention.

FIG. 2 is a front view of FIG. 1.

FIG. 3 is a back view of FIG. 1.

FIG. 4 is a left side view of FIG. 1.

FIG. 5 is a right side view of FIG. 1.

FIG. 6 is a top plan view of FIG. 1; and,

FIG. 7 is a bottom plan view of FIG. 1.

The broken lines depict portions of the electric breast pump that form no part of the claimed design.
